CLAIM

The ornamental design for a cake turntable, as shown and described.

DESCRIPTION

FIG. 1 is a front and top perspective view of a cake turntable, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of area 9 circumscribed within FIGS. 1; and,

FIG. 10 is an enlarged detail view of area 10 circumscribed within FIG. 2.

The dash-dot-dash broken lines circumscribing the areas of the details in FIGS. 1 and 2 and surrounding FIGS. 9 and 10 denote the boundaries of the enlarged detail views and form no part of the claimed design.
